UNITED STATES PATENT OFFICE

THOMAS J. PARKER, OF CHICAGO, ILLINOIS, ASSIGNOR OF ONE-HALF TO WILLIAM
McGUINEAS, OF CHICAGO, ILLINOIS

INTERNAL COMBUSTION ENGINE

Application filed January 17, 1930. Serial No. 421,480.

This invention relates to improvements in internal combustion engines. The invention is adapted to be embodied in radial motors and in motors in which parallel cylinders are arranged in alignment.

One of the objects of the invention is to produce a multiple cylinder 2-cycle engine in which each cylinder is enclosed to form a compression and explosion chamber at the front end of the piston and a compression chamber at the rear of the piston.

Another object is to provide connections between the piston and the crank shaft whereby the piston will be relieved of side thrust, and the piston rod will be caused to move in an axial direction coincident with the axis of the cylinder.

Another novel feature is the universal connection for connecting the piston rod to the piston.

Another object is to provide in a radial engine a master bearing for connecting one of the piston rods to the crank shaft whereby stability and smoothness of operation are assured.

The advantages resulting from these novel features of construction will more fully appear as I proceed with my specification.

In the drawings:

Fig. 1 is a transverse vertical sectional view of a radial motor.

Fig. 2 is a longitudinal vertical section taken on the line 2—2 of Fig. 1.

Fig. 3 is a plan view of Fig. 2.

Fig. 4 is an enlarged view of the connecting rod unit detached from the crank shaft.

Fig. 5 is a horizontal section of a detail of construction taken on the line 5—5 of Fig. 1, looking downwardly as indicated by the arrows.

Fig. 6 is a vertical section taken at right angles to the view shown in Fig. 5, the same being taken on the line 6—6 of Fig. 5.

Fig. 7 is a longitudinal vertical sectional view, partly in elevation, showing the invention as embodied in an engine having the cylinders in alignment.

Fig. 8 is a plan view of the engine shown in Fig. 7.

Referring now to that embodiment of

the invention shown in Figs. 1 to 6 inclusive, the crank case is indicated at 10, the same being cast in two parts which are connected together by bolts extending through the flanges 11. The crank case is provided with four circular openings for the cylinders which are radially disposed and spaced apart equidistantly circumferentially of the crank case. Each of the cylinders comprises a tubular body 12 closed at its outer end 13 and having a circumferential marginal flange 14 extending outwardly from the margin of the body 12 to be seated on the outer surface of the crank case 10 surrounding the aperture therein.

The inner end of the cylinder 12 is closed by a cup shaped member 15 which also has a circumferential marginal flange 16 similar to the flange 14. The flange 16 rests against the inner surface of the crank case 10 opposite the flange 14. Bolts and nuts 17 extend through the flanges 14 and 16 and through the crank case wall 10 and securely connect the cylinder 12 and cup shaped member 15 to the crank case.

The cup shaped member 15 has a central opening surrounded by an inwardly directed tubular flange 18 which forms a bearing for the piston rod. The outer end of the cylinder 12 is preferably provided with radiating fins 19, and a conventional spark plug 20 extends into the cylinder through the end 13.

A hollow cylindrical piston 21 having a curved front end 22 is slidably mounted in each cylinder 12 and closely engages the cylindrical walls of the cylinder. Piston rings 21' are provided as shown. Extending across the interior of the piston 21 is a wrist pin 23 fixed in the cylindrical piston walls in bearings 24. On the pin 23 is mounted a sleeve-like member 25 carrying trunnions 26 which extend from opposite sides of the member 25, axially, at right angles to the pin 23. The member 25 is preferably formed with its longitudinal walls tapering from the middle toward each end where they engage the pin but the exact shape is not essential. The member 25 is adapted to have reciprocating rotative motion relative to the pin 23.

The piston rod is bifurcated to form parallel, spaced apart arms 28, each apertured near its end and pivotally mounted on a trunnion 26. The opposite end of the piston rod 27 5 is slightly enlarged and apertured for receiving a pin 29 for connecting the piston rod to a connecting rod 30. Each connecting rod 30 is bifurcated as indicated at 31, to receive the end of the piston rod 27 which is held 10 by the pin 29, as stated. At its other end, each connecting rod 30 is pivotally connected to a hub 32 which is rotatably mounted on the bearing 33 of the crank shaft 34. This hub 32 is formed with radially extending 15 ears 35. These ears are in pairs, the ears of each pair being spaced apart to receive the end of the connecting rod 30, held in place by a pin 35'. There are three pairs of ears 35 spaced 90° apart on the hub 32, each to 20 receive a connecting rod 30. The fourth connecting rod is indicated at 30' in Fig. 4 and this one is rigidly secured to or integral with the hub 32.

The hub 32 is preferably made in two 25 parts, each of which has edge flanges 36 by which the two parts of the hub are connected together after the hub is mounted on the crank shaft as indicated at 37.

The connections between the bearing 33 and 30 the piston 21 are such that the piston is relieved of side thrust, in the operation of the engine, the piston rod moving longitudinally in a line coincident with the axis of the cylinder. The universal joint provided by the 35 parts shown in detail in Figs. 5 and 6 insures accurate longitudinal reciprocation of the piston in the cylinder, the piston rod 27 being guided in the bushing 38 in the bearing 18.

40 It will be understood that the connecting rods 30 may be increased in length and the crank case increased accordingly, to decrease side thrust on their bearings; the present proportions of the parts having been selected 45 for this drawing on account of lack of more space to show the assembled parts.

The crank shaft 34 at one end extends outwardly from the crank case 10 and carries the conventional propeller indicated at 39. 50 At its opposite end the crank shaft 34 carries a timer indicated as a whole at 40. 41 indicates an oil tank and pump which is also operatively connected to the crank shaft.

Each of the cylinders 12 is provided with 55 a fuel inlet 42 in communication through the intake manifold 43 with a carburetor indicated as a whole at 44.

45 indicates the connection of the four intake lines 43 and carburetor. Each of the 60 intake lines 43 communicates with a cylinder 12 through the inlet port 42 to permit fuel to enter the cylinder rearwardly of the piston when the piston is in a sufficiently forward 65 position in the cylinder to open the port 42. Communication is established between the

chambers at opposite ends of the piston in the cylinder by an intake conduit 46 which extends from the inner end of the cylinder at the rear of the piston to the intake compression chamber 47 which is located forwardly of the piston when the piston is in its most rearward position. The exhaust port 48 is opposite the intake 47.

The operation of the radial motor is as follows:—

Taking for example, the cylinder 12 at the top of Fig. 1, when the piston is moved rearwardly, that is to say, toward the cup-shaped end 15, the fuel which has entered the compression chamber 49 through the fuel port 42 will be compressed. When the piston has proceeded rearwardly sufficiently to bring the intake compression chamber 47 into communication with the compression-explosion chamber 50 at the forward end of the cylinder, the compressed fuel will rush through the conduit 46, chamber 47 and into the cylinder chamber 50. The return stroke of the piston from the rear to the forward end compresses the fuel in the chamber 50, the spark being timed accordingly, so that explosion takes place in the chamber 50, and the piston is caused to move rearwardly, opening the exhaust 48 for its intended purpose.

Referring now to the embodiment of the invention shown in Figs. 7 and 8, in which the cylinders are vertically disposed and in horizontal alignment, the construction of the cylinders 60 with the cup shaped enclosure 61 for forming closed cylinders is similar to the corresponding parts 12 and 15 described in connection with the radial motor. Likewise the piston rod 62 is connected to the piston 63 by the type of universal connection heretofore described, comprising the parts shown in detail in Figs. 5 and 6, and the piston rod is arranged for movement in an axial direction coincident with the axis of the cylinder, being guided in bearings 62' in the bottom of the cylinder.

The piston rod 62 is pivotally connected to the connecting rod 64, which is connected to the hub 64' on crank shaft 65 in a familiar manner. The manifold intake 66 communicates with the intake ports 67 of the compression chamber 68 below or rearwardly of the piston 63 and the compression chamber 68 communicates through conduit 69 with the intake compression chamber 70 which is, during part of the operation, in communication with the compression-explosion chamber 71 at the top or forward end of the cylinder. The exhaust 72 communicates with the several cylinders through the exhaust ports 73.

74 indicates a timer operatively connected with the crank shaft, 75 is the fan belt, and 76 a fly wheel. 77 indicates a carburetor, 78 the spark plugs and 79 the crank case.

From the foregoing it will be understood that the closing of each cylinder by the cup-

shaped member herein described results in producing a compression chamber at one side and a compression-explosion chamber at the other side of each piston in each cylinder, 5 and avoids the necessity of having separate crank cases for each cylinder. The efficiency of the engine as compared to two-cycle engines having open ended cylinders, is substantially increased.

10 The universal connection between the piston rod and piston and the reciprocation of the piston rod in an axial direction coincident with the axis of the cylinder is another important feature of the invention; it relieves the piston from side thrust and reduces the wear on the piston and cylinder to a negligible quantity.

15 The rigid connection between the master connecting rod 30' and the hub 32 is a feature of improvement which is particularly valuable in a radial engine, whereas the other advantages herein referred to are attained when the invention is embodied in either a radial or a straight line engine.

20 25 The engine of the present invention is known as a multi-power engine. The power developed by my four-cylinder, two-cycle engine is substantially in excess of that developed by an eight-cylinder, four-cycle engine 30 having cylinders of equal bore and length of piston stroke, and I attribute this efficiency and the smoothness of operation of my device to the fact that just before the compression stroke of one piston is completely finished, the compression stroke of 35 another piston is commenced.

Obviously, changes in details of construction may be made without departing from the scope of my invention, and I do not intend to be limited to the exact form of construction described, except as set forth in the appended claims.

40 45 50 55 1. A radial two-cycle internal combustion engine comprising a crank case, a crank shaft mounted in the case, the crank case being apertured at a plurality of places spaced equidistantly circumferentially of the case, a cylinder closed at one end and flanged adjacent its open end secured to the crank case with the flange surrounding one of said openings, a cup-shaped member secured to the inside of the crank case to close the open end of the cylinder, a piston movable in the cylinder, a piston rod connected to the piston and extending through an aperture in said cup-shaped member into the crank case, and pivotal connections between the piston rod and the crank shaft.

60 65 2. A two-cycle internal combustion engine comprising a crank case, a crank shaft mounted in the case, the crank case being apertured at a plurality of places, a cylinder closed at one end and flanged adjacent its open end, secured to the crank case with the flange surrounding one of said openings, a

cup-shaped member secured to the inside of the crank case to close the open end of the cylinder, a piston movable in the cylinder, a piston rod connected to the piston and extending through an aperture in said cup-shaped member into the crank case, and pivotal connections between the piston rod and the crank shaft. 70

3. A two-cycle internal combustion engine comprising a crank case, a crank shaft mounted in the case, the crank case being apertured at a plurality of places, a cylinder closed at one end and flanged adjacent its open end, secured to the crank case with the flange surrounding one of said openings, a cup-shaped member secured to the inside of the crank case to close the open end of the cylinder, an auxiliary compression chamber adjacent the cylinder and in communication with the interior of the cylinder, a conduit extending from the cup-shaped member to the auxiliary compression chamber, a piston movable in the cylinder, a piston rod connected to the piston and extending through an aperture in said cup-shaped member into the crank case, and pivotal connections between the piston rod and the crank shaft. 80

4. A two-cycle internal combustion engine comprising a crank case, a crank shaft mounted in the case, the crank case being apertured at a plurality of places, a cylinder closed at one end and secured adjacent its open end to the crank case, a cup-shaped member within the crank case for closing the open end of the cylinder, a piston movable in the cylinder, an inlet port in the cylinder wall located below the piston when the latter is in its forward position, an auxiliary compression chamber adjacent the forward end of the cylinder and communicating with the interior of the cylinder, a conduit extending from the cup-shaped member to the auxiliary compression chamber, the auxiliary chamber being in communication with the cylinder when the piston is in its rearward position. 90

5. A two-cycle internal combustion engine comprising a crank case, a crank shaft mounted in the case, a cylinder closed at one end and open at the other mounted on the crank case, the crank case having an opening registering with the open end of the cylinder, a cup-shaped member secured to the crank case to close the open end of the cylinder, the cup-shaped member being centrally apertured, a bushing surrounding the aperture, a piston movable in the cylinder, a piston rod connected to the piston and extending through said apertured cup-shaped member into the crank case and pivotal connections between the piston rod and the crank shaft. 100

In testimony that I claim the foregoing as my invention, I affix my signature, this 10th day of January, 1930.

THOMAS J. PARKER.
